(57) **CLAIM**

The ornamental design for the smart bollard, as shown and described.

DESCRIPTION

FIG. 1 is top, rear and side perspective view of a smart bollard showing their new design;

FIG. 2 is a top, front and side perspective view of the smart bollard of FIG. 1;

FIG. 3 is a front elevational view of the smart bollard of FIG. 1;

FIG. 4 is a rear elevational view of the smart bollard of FIG. 1;

FIG. 5 is a side elevational view of the smart bollard of FIG. 1, with the other side being a mirror image of this side;

FIG. 6 is a top plan view of the smart bollard of FIG. 1;

FIG. 7 is a bottom plan view of the smart bollard of FIG. 1;

FIG. 8 is cross-sectional elevational view taken along the line 8-8 in FIG. 6 of the smart bollard of FIG. 1; and,

FIG. 9 is a cross-sectional view taken along the line 9-9 in FIG. 6 of the smart bollard of FIG. 1.

1 Claim, 9 Drawing Sheets
